UNITED STATES PATENT OFFICE.

GEORGE E. MILLER, OF PAWTUCKET, RHODE ISLAND.

ROOF-BRACKET.

SPECIFICATION forming part of Letters Patent No. 496,483, dated May 2, 1893.

Application filed September 17, 1892. Serial No. 446,238. (No model.)

To all whom it may concern:

Be it known that I, GEORGE E. MILLER, a citizen of the United States, residing at No. 9 Johnson street, in the city of Pawtucket, 5 county of Providence, and State of Rhode Island, have invented a certain new and useful Improvement in Roof-Brackets, of which the following is a specification.

My said invention relates to a shingling bracket used for the purpose of securely supporting stagings and platforms on roofs and other inclined surfaces, and consists of a solidly riveted framework of steel, or other suitable material, formed in the one part to fit a 10 slanting roof or inclined surface, and of a proper shape in the other part to support and secure the staging or platform placed thereon, and provided with a clamp and hooked spurs to firmly fasten the device to the roof or surface aforesaid.

The accompanying drawings are hereby made part of this specification, similar letters of reference thereon referring to corresponding parts.

25 Figure 1 is a plan or top view of the device, showing part of a shingled roof surface underneath, and Fig. 2 is a side view of the bracket and a transverse sectional view of the part of a roof seen in Fig. 1, the bracket being secured thereto and in position ready 30 to receive platform or staging boards to be placed thereon.

a a a a represent the shingles on the plane of the roof seen at b b.

35 The bracket is in two parts or pieces, c being the formed base so curved at one end as to form the loop or clamp d, the end terminating in two or more hooked spurs one of which is shown at e.

40 f f f f is the shaped frame formed of one piece of stock and firmly riveted to the base c d by the large rivets i i, while one of its ends is securely fastened to the horizontal plane n n by the spur-top rivet k. When the two 45 members of the device are so riveted together as shown they become a firm and solid whole without any movable or sliding parts. The curved or looped end d is so shaped as to form a clamp to fit upon the tapering surface of the 50 end of the lower row of shingles, the weight of

the added staging and workmen on the plane n n compelling this clamp to clasp the upward tapering end of the shingles more and more tightly as the weight of, and on, the staging is increased. The hooked and sharpened 55 spurs e, one at each corner of the end of the base beyond the loop d, (and one or more between these two if desired,) are forced into the row of shingles lying underneath the one clamped by said loop, and penetrate deeper 60 and deeper into it as the strain upon the bracket grows greater.

The manner of attaching the device to the roof is shown in Fig. 2. The projecting top c is inserted under the upper row of shingles 65 as seen and extends thereunder some four or five inches, and more if desired; the loop or clamp d receives the end of the second row of shingles next below the one above mentioned as the end of the base is pushed upward to 70 place. The end of the last mentioned row of shingles will be slightly raised for the purposes described, and when it is released to its former position the hooked and sharpened spurs e at once fasten themselves into the row 75 of shingles next below. On an ordinary roof this will leave the plane n n nearly horizontal for the staging boards or platform planks: the spur k will be nearly or quite vertical, and in the required relation to firmly hold the 80 staging or platform aforesaid.

It will be apparent how great strength and security are attained as the hooked and sharpened spurs e sink deeper and deeper into the under row of shingles, reinforced by the increasing grip of the clamp d on the tapering ends of the row of shingles next above, and both steadied by the projecting end of the base c well thrust between the two upper and independent rows of shingling as shown: and 90 it will also be clear that the more the weight and strain upon the bracket are increased the stronger and more secure will be the grip and hold of the several parts upon the roof. The device will afford workmen almost absolute 95 safety upon any roof of any inclination, and may be applied and removed with great ease and rapidity. From its simplicity it may be made at small cost, and will last an indefinite period. Its use leaves no injury to the roof 100

or shingling, the hooked spurs entering an under row of shingling at least two inches above the weather line.

This device is not confined to shinglers' 5 and carpenters' use, but may be used by painters, masons, and all others whose employments require them to go upon inclined surfaces.

Having thus described my said invention, what I claim as new, and desire to secure by 10 Letters Patent, is—

A shingler's bracket made from two pieces of steel, or other suitable material, the base *c* having its end *d* looped to form a clamp

and terminating in two or more hooked spurs, and the bent frame *ff* solidly riveted to the 15 base as at *i i*, with its supporting end also firmly secured to its staging plane *nn* by means of the spur-top rivet *k*: all of said parts being constructed and combined in the manner and for the uses and purposes substantially as shown and described.

GEORGE E. MILLER.
